UNITED STATES PATENT OFFICE.

GEORGE HENRY ELWELL, OF DETROIT, MICHIGAN, ASSIGNOR TO CHESTER F. HARDON,
TRUSTEE, OF BROOKLINE, MASSACHUSETTS.

DOOR-LATCH.

1,356,612.

Specification of Letters Patent. Patented Oct. 26, 1920.

Application filed August 5, 1918. Serial No. 248,402.

To all whom it may concern:

Be it known that I, GEORGE HENRY ELWELL, a citizen of the United States, residing at Detroit, in the county of Wayne and State of Michigan, but formerly of Boston, in the county of Suffolk and State of Massachusetts, have invented certain new and useful Improvements in Door-Latches, of which the following is a specification.

10 My invention relates to improvements in door latches and more particularly to that class of latches employing a bolt with a hook-shaped head for positive interlocking engagement with the striker-plate.

15 The objects of my invention are to provide a latch bolt fully adapted to the elasticity of motor car bodies and like uses; to provide a positive lock insuring safety to occupants of the car employing it; to provide 20 a latch in itself anti-rattle, without the assistance of rubber bumps on the door stops; and to provide a latch, the closing action of which is so easy as to make slamming of the door unnecessary.

25 With this and other objects in view, as will more fully hereinafter appear, the invention consists in certain novel features of construction and arrangement of parts hereinafter described, illustrated in the accompanying drawings and particularly pointed out wherein patentable novelty is claimed for certain features of the device, it being understood that within the scope of what hereinafter thus is claimed various changes 30 in form, proportion, size, and minor details of the construction can be made without departing from the spirit or modifying any of the advantages of the invention.

35 The following is the description of an embodiment of my invention, reference being had to the accompanying drawings:

In the accompanying drawings, Figure 1 is an upright view of the mechanism of the device;

45 Fig. 2 is a bottom view of the preceding figure;

Fig. 3 is a face view of the preceding figure;

50 Fig. 4 is an upright view of the mechanism, with double control;

Fig. 5 is top view of the preceding figure;

Fig. 6 is a face view of the preceding figure;

55 Fig. 7 is a back view of the preceding figure;

Fig. 8 is an upright view of the mechanism adapted for lever cam control;

Fig. 9 is a bottom view of the preceding figure;

Fig. 10 is a face view of the preceding 60 figure;

Fig. 11 is an end view and a face view of striker-plate; and

Fig. 12 is a face view and an end view of a modified striker-plate.

Referring more particularly to the drawings,—

A supporting plate or incasement 1 is provided with a face 2 having a perforation 3, said incasement 1 being also provided 70

with a back 4 having a passage 5, said face 2 with its perforation 3 and back 4 with its

passageway for bolt 6, and said face 2 with its 75

perforation 3 reinforced by strap or cover 7

providing guiding bearings for said bolt 6 sliding in its passageway, as shown by

Figs. 1, 2, 3, 4, 5, 6, 7, 8, 9, and 10. The

bolt 6 is provided with a double beveled head 8 for engaging the striker-plate 26 both 80

upon entering and leaving said striker-plate 26, said bolt head 8 forming a rigid hook,

and said bolt 6 is also provided with an auxiliary bolt member 9 carried by said bolt 6,

as shown in Figs. 1, 2, 3, 4, 5, 6, 8, 9, and 10. 85

The incasement 1 is also provided with a movable conveyer 10 maintained in its normal forward position in the passageway of

said bolt 6 by means of spring 11 and arrested in its forward movement by check 90

12 with which incasement 1 is provided, the rearward tension of said spring 11 being held

in check by back 4 of said incasement 1. Said bolt 6 is provided with shoulders 13 and 14

engaging conveyer 10 and the rearward end 95

of said spring 11, respectively, so that said conveyer 10 and said spring 11 when they

are in their normal positions are lying between and engaging said shoulders 13 and

14 of said bolt 6. Washer 15 may be placed 100

between said spring 11 and said shoulders 14, as shown in Figs. 1, 2, 4, 5, 8, and 9.

Said auxiliary bolt 9 is held in its normal position by spring 16 with which said bolt 6 is provided, the rearward end of said 105

spring 16 engaging said shoulders 13 of said bolt 6 and exerting its tension in a forward direction against yoked end 17 of said auxiliary bolt 9, as shown in Figs. 1, 2, 4, 5, 8,

and 9. Lever 18 may be pivoted to said bolt 110

6 to operate said auxiliary bolt 9 against the tension of said spring 16, as shown in Figs. 1 and 2. If desired, said lever 18 may be pivoted to said incasement 1 to operate said 5 conveyer 10 against the tension of said spring 11, as shown in Figs. 4 and 5. A cam 19 may be pivoted to said lever 18 and one end of said cam 19 made to engage and operate said conveyer 10 upon the rearward 10 movement of said lever 18 and an engagement of the opposite end of said cam 19 with a shoulder 20 with which said incasement 1 is provided, as shown in Figs. 8, 9, and 10. When the said lever 18 is pivoted to said 15 incasement 1, said check 12 with which said incasement 1 is provided is made to arrest the movement of said lever 18 and then said lever 18 arrests the forward movement of said conveyer 10, as shown in Figs. 4 and 20 9. When said lever 18, either by direct engagement or by means of said cam 19 is made to operate said conveyer 10, said conveyer 10 is provided with a forward arm bent to form shoulders 21 made to engage 25 yoke end 17 of said auxiliary bolt 9 upon a sufficient operation of said conveyer 10, as shown in Figs. 5 and 9. If desired, the said forward arm of conveyer 10 may be made to lie and operate in a slot 22 with which incasement 1 may be provided, as shown in 30 Figs. 8 and 9. An operating rod 23 may be pivoted to said lever 18 when said lever 18 is bent to provide for either a lift-up operation or a push-down operation, as shown 35 in Figs. 1 and 4, respectively. A wing 24 with which conveyer 10 may be provided may provide the means by which said conveyer 10 may be operated independently from the movement of said lever 18, said 40 wing 24 being operatively engaged by spindle cam 25, as shown by Fig. 4. When said strap 7 is made to cover the entire bolt passage as shown in Fig. 4 back 29 may be provided by said strap 7 to take the place of 45 back 4 provided by said incasement 1, as shown in Fig. 7. A striker-plate 26 is provided with perforation 27 to receive said bolt head 8 carrying said auxiliary bolt 9. When said auxiliary bolt 9 is carried externally by said bolt head 8 said striker-plate 50 26 is provided with a bumper section 28, as shown in Figs. 2 and 11. But when said auxiliary bolt 9 lies and is carried in a groove with which said bolt head 8 is provided said bumper section 28 is omitted, as 55 shown in Figs. 4, 5, and 12.

In operation the closing bevel of head 8 60 engages striker-plate 26 and compresses bolt 6 against the tension of spring 11 and as the door is swung to a closed position bolt head 8 obliquely enters perforation 27 of striker-plate 26 and auxiliary bolt 9 engaging the portion of said striker-plate 26 65 bounding said perforation 27 is thereby compressed against the tension of spring 16

to permit the entrance of said head 8 into said striker perforation 27, and the rigid hook portion of said head 8 to take its interlocking position with relation to said striker-plate 26. When auxiliary bolt 9 reaches a position in alinement with said 70 perforation 27 and is thus released from its engagement with said striker-plate 26 it also enters said perforation 27 and resumes its normal position, thus blocking the withdrawal of said bolt 6 from said perforation 27 in said striker-plate 26, as shown in Fig. 2.

When the head of said auxiliary bolt 9 is slightly beveled, as shown in Fig. 5, at 30 80 said bolt 9 does not necessarily resume its full normal position upon entering said perforation 27, but wedges itself into said perforation 27 between the opening bevel of bolt head 8 and the bounding surface of 85 said perforation 27, thus being adapted to take up variances occurring in manufacture and also providing for slight wear.

When interlocked with said striker-plate 90 26, bolt head 8 may be extended in any circumstances that may tend to increase the distance between the striker-plate 26 and face 2 of lock incasement 1, shoulder 14 of bolt 6 compressing spring 11 in a forwardly direction, said spring 11 being held at its 95 opposite end by conveyer 10 arrested in its forward movement by check 12, as shown in Figs. 2 and 9, or by lever 18 as shown in Figs. 4 and 8.

The interlocking engagement between bolt 100 6 and striker-plate 26 may be released by lever 18 operatively engaging and operating said auxiliary bolt 9, as shown in Figs. 1 and 2, or lever 18 may operate conveyer 10, consecutively compressing spring 11 and 105 operating said auxiliary bolt 9, as shown in Figs. 4, 5, 8, and 9. Any means of operating said lever 18 may be employed, but when said lever 18 is pivoted to said incasement 1 below said bolt 6 so as to operatively swing 110 under said bolt 6 by a rearward movement of the free end of said lever 18, cam 19 pivoted to said lever 18, its upper end engaging shoulder 20 of incasement 1 and its lower end engaging said conveyer 10, may 115 be made to operate said conveyer 10 the maximum distance with the minimum rearward movement of said lever 18.

When auxiliary bolt 9 is withdrawn from 120 said perforation 27 in striker-plate 26, in the manner above described, the door may be swung open, the opening bevel of said bolt head 8 engaging the bounding surface of said perforation 27, compressing said bolt 6 as in closing. When said conveyer 10 is 125 operated by lever 18, the tension of said spring 11 is wholly removed from said bolt 6 before shoulder 21 of said conveyer 10 engages and operates said auxiliary bolt 9, thus insuring an easy opening swing of the 130

door as the opening bevel of said bolt head 8 in its engagement with the bounding surface of said perforation 27 meets no spring tension resistance.

5 As will be evident to those skilled in the art, my invention permits of various modifications without departing from the spirit thereof or the scope of the appended claims:

What I claim is:

10 1. A door latch comprising a proper incasement; a latch bolt provided with means for interlocking engagement with a striker-plate; rigid guiding bearings with which said incasement is provided for slidably 15 mounting said bolt to normally project from said incasement; spring means permitting said latch bolt to be moved in either direction from a normal intermediate position and adapted to return said latch bolt to said 20 intermediate position; and means to retire said bolt from said interlocking engagement.

25 2. A door latch comprising a proper incasement; a latch bolt provided with a rigid hook-shaped head for interlocking engagement with a striker-plate and carrying a yielding auxiliary bolt member; rigid guiding bearings with which said incasement is provided for slidably mounting said bolt 30 to normally project from said incasement; spring means to advance and maintain said latch bolt and said auxiliary bolt in their normal latching positions; and manually operative means for operating said auxiliary 35 bolt and said latch bolt.

40 3. A door latch comprising a proper incasement; a latch bolt provided with a beveled head forming a rigid hook; rigid guiding bearings with which said incasement is provided for slidably mounting said bolt to normally project from said incasement; spring means permitting said latch bolt to be moved in either direction from a normal intermediate position and adapted 45 to return said latch bolt to said intermediate position; and means to retire said bolt head within said incasement.

45 4. A door latch comprising a proper incasement, said incasement being provided 50 with a bolt passage extending through the face of said incasement; spring means mounted in said passage and exerting its tension in forward and rearward directions; means with which said incasement is provided within said bolt passage to arrest in both directions the tension of said spring means; a latch bolt provided with a beveled head forming a rigid hook for interlocking engagement with a striker-plate, said bolt 55 being slidably mounted within said bolt passage; shoulders with which said latch bolt is provided normally engaging the tension in both directions of said spring means; and manually operative means to retire said

bolt head from said interlocking engagement and within said incasement. 65

5. A door latch comprising a proper incasement; a latch bolt having a rigid hook-shaped head for positive engagement with a striker-plate; an auxiliary bolt carried by 70 said latch bolt head, said latch bolt and said auxiliary bolt being slidably mounted within said incasement and capable of being advanced together through a perforation with which the face of said incasement is provided; spring means with which said auxiliary bolt is provided; spring means to advance and maintain said latch bolt in its normal latching position; and manually operative means for operating said auxiliary 80 bolt and said latch bolt against their respective spring means.

6. A door latch comprising a proper incasement; a latch bolt having a rigid hook-shaped double beveled head; an auxiliary 85 bolt carried by said latch bolt head; spring means against the tension of which the auxiliary bolt is capable of being compressed independently from the compression of said latch bolt; spring means permitting 90 said latch bolt to be moved in either forward or rearward direction from a normal intermediate position and adapted to return said latch bolt to said intermediate position; and manually operative means for operating 95 said auxiliary bolt.

7. A door holding means comprising a striker-plate having means for attachment to a door-frame; a latch mechanism having means for attachment to a door and comprising a proper incasement; a beveled head latch bolt slidably mounted within said incasement and being capable of advancing from within said incasement; spring means with which said bolt is provided to advance 100 and maintain said bolt in an extended position greater than normal latching position; and manually operative means to retire said bolt within said incasement and to return said bolt to a normal latching position; 105 whereby said bolt is adapted to rest in a normal latching position when the door is in an open position; and whereby said bolt is adapted to maintain a fixed engagement with the striker-plate under all fluctuating 110 relative positions of the door and door-frame when the door is in its closed position.

8. A door holding means comprising a striker-plate and a latch mechanism having 115 a proper incasement and provided with a two section hook-shaped head latch bolt normally projecting from and slidably mounted within said incasement, said two section head of said latch bolt in normal position 120 being of greater diameter than the bolt head passage provided by said striker-plate, and one of said bolt head sections yielding to

- diminish said diameter upon the engagement of said bolt head with said striker-plate, the inner surface of the hook portion of said bolt head engaging the rearward surface of 5 and becoming positively interlocked with said striker-plate; spring means to maintain said bolt head sections in their normal positions and to return said bolt head to its normal latching position when said bolt has 10 been compressed or has been extended by external means beyond said normal latching position; whereby said latch bolt head is adapted for interlocking engagement with said striker-plate only by separate and full 15 engagements of said bolt head sections; and whereby said interlocking engagement may be released only by the separate yielding of one of said bolt head sections; and whereby the latch bolt while interlocked with said 20 striker-plate may be extended beyond normal latching position.
9. An anti-rattle safety extension bolt door holding means comprising a striker-plate and a latch mechanism comprising a 25 proper incasement, said incasement having a face provided with a perforation, said perforation being reinforced by a strap providing bolt guiding bearings; a latch bolt having a double beveled head, said head forming 30 a rigid hook; an auxiliary bolt carried by said latch bolt head, said latch bolt being slidably mounted in the bolt passage provided by said incasement and capable of advancing through said reinforced perforation 35 to and beyond normal latching position; spring means exerting its tension against said auxiliary bolt and against a shoulder with which said latch bolt is provided; spring means exerting its tension in a forwardly direction against a conveyer mounted 40 in said latch bolt passage and arrested in its forward movement by a check with which said incasement is provided and normally in a rearwardly direction against a back 45 provided by said incasement, said latch bolt being provided with shoulders that normally engage the forward surface of said conveyer and the rearward extremity of said spring means, said spring means permitting said 50 latch bolt to be moved in either direction from a normal intermediate position and adapted to return said latch bolt to said intermediate position; and manually operative means to retire said auxiliary bolt within 55 said incasement, said means comprising a lever pivoted to said latch bolt and operatively engaging said auxiliary bolt.
10. An anti-rattle safety extension bolt door holding means comprising a striker-plate and a latch mechanism comprising a proper incasement, said incasement being provided with a bolt passage extending through the face of said incasement; a latch bolt having a double beveled head, said head 60 forming a rigid hook; an auxiliary bolt car-

ried by said latch bolt head, said latch bolt being slidably mounted in said bolt passage and normally projecting from said face of said incasement to normal latching position; spring means to maintain said auxiliary bolt 70 in its normal position; spring means to advance and maintain said latch bolt in its normal latching position, said spring means permitting said latch bolt to be moved in either forward or rearward direction from 75 a normal intermediate position and adapted to return said latch bolt to said intermediate position; and manually operative means for rearwardly compressing said spring means of said latch bolt and operating said auxiliary bolt, said operative means comprising a vertical lever pivoted to the lower portion of said incasement, said lever being provided with a cam lever pivoted to said vertical lever, the upper portion of said cam 80 lever engaging a shoulder with which said incasement is provided and the lower portion of said cam lever engaging a conveyer holding the forward extremity of said latch bolt spring means, said conveyer having a forward arm for engagement with said auxiliary bolt when said conveyer is sufficiently operated; whereby said vertical lever is adapted to be swung rearwardly, causing the cam lever to operate said conveyer and compress said latch bolt spring means the maximum distance for the minimum movement of said vertical lever, thus first removing the spring tension from said latch bolt and then operating said auxiliary bolt.

11. An anti-rattle safety extension bolt door holding means comprising a striker-plate and a latch mechanism comprising a proper incasement, said incasement being provided with a bolt passage extending 105 through the face of said incasement; a latch bolt having closing and opening bevels with which the head of said latch bolt is provided, said head forming a rigid hook; an auxiliary bolt having a slightly beveled head and being 110 slidably seated in a groove in the opening bevel side of said latch bolt head by which said auxiliary bolt is carried, said latch bolt being slidably mounted within said bolt passage and normally projecting from the said 115 face of said incasement to normal latching position; spring means to maintain said auxiliary bolt in its normal forward position; spring means to advance and maintain said latch bolt in its normal latching position, said spring means permitting said latch bolt to be moved in either forward or rearward direction from a normal intermediate position and adapted to return said latch bolt to 120 said intermediate position; and manually operative means for rearwardly compressing said latch bolt spring means and operating said auxiliary bolt; whereby said latch bolt is adapted to be compressed against its spring means upon an engagement of said 125 130

closing bevel with said striker-plate and said latch bolt head to obliquely enter the striker-plate passage, said auxiliary bolt yielding until said hook portion of said latch bolt head interlocks with the rearward surface of said striker-plate when the beveled head of said auxiliary bolt wedges into said striker-plate passage between the opening bevel of said latch bolt head and the surface 5 of said striker-plate bounding said passage; and whereby said latch bolt is adapted to be easily compressed upon an engagement 10

of said opening bevel with said striker-plate when said spring tension is first removed and said auxiliary bolt withdrawn from its 15 wedged engagement in said striker-plate passage by said manually operated means.

In testimony whereof I have affixed my signature in presence of two witnesses.

GEORGE HENRY ELWELL.
